ULTRASONIC MOTION DETECTOR ALARM

Michael S. Weinstock, 3453 Green Vista Drive,
Encino, Calif. 91316

Filed Jan. 10, 1969, Ser. No. 15,303

Term of patent 14 years

Int. Cl. D29—99

U.S. Cl. D72—1

FIGURE 1 is a front perspective view of an ultrasonic motion detector alarm device embodying my new design;

FIGURE 2 is a right side elevational view of the alarm shown in FIGURE 1;

FIGURE 3 is a bottom plan view of the alarm shown in FIGURE 1; and

FIGURE 4 is a rear elevational view of the alarm shown in FIGURE 1.

I claim:

The ornamental design for an ultrasonic motion detector alarm, as shown.
